UNITED STATES PATENT OFFICE.

BANCROFT G. BRAINE, OF MONTCLAIR, NEW JERSEY, ASSIGNOR TO THE RAIL JOINT COMPANY, OF NEW YORK, N. Y., A CORPORATION OF NEW YORK.

MEANS FOR BALANCING STRESSES IN RAIL JOINTS.

1,406,528.

Specification of Letters Patent. Patented Feb. 14, 1922.

Application filed September 24, 1920. Serial No. 412,557.

To all whom it may concern:

Be it known that I, BANCROFT G. BRAINE, citizen of the United States, residing at Montclair, in the county of Essex and State of New Jersey, have invented certain new and useful Improvements in Means for Balancing Stresses in Rail Joints, of which the following is a specification.

This invention relates to rail joints and particularly to a novel modification in the distribution of metal in a rail joint bar to better balance stresses therein, thereby reducing the liability to rupture under service conditions.

Because of the requirement of adapting the design of a joint bar to a fit with the rail and also to meet certain other service conditions, some of the fibres which are most remote from the horizontal neutral axis are not scientifically disposed from the standpoint of strength, being therefore susceptible of rupture. And, in certain types of bars, the supplemental distribution of metal produces an unduly high ratio of disproportion between the section modulus of the top chord of the bar and the section modulus of the bottom of the bar. This creates a condition, particularly in the top of the bar, where the extreme top fibres are located in an area of the metal that is inadequate to withstand the strains imposed upon these extreme top fibres.

Accordingly, the present invention contemplates an improvement for deflecting the load stress to a point below the inadequate area of metal, above referred to, and in the case of the head of the bar leaves practically all of the fishing surface at the top of the bar to serve as a support for the underside of the rail head, but practically eliminates it as a factor in the theoretical calculation of the strength of the bar. In other words, the invention proposes to establish or locate a desirable area of metal bearing a proper relation to the distribution of metal throughout the bar so as adequately to meet the requirements of maximum stresses imposed on the head of the bar, thus better safeguarding the bar against the opening of cracks or sudden rupture.

The foregoing general object may be conveniently carried into execution by so altering the original distribution of metal at the top of the bar, as in effect, to establish a top

chord composed of fibres uniformly distant from the neutral axis of the bar. That is to say, the invention contemplates the formation of a construction to eliminate excessive strain in the small area at the top of the bar section by modifying the rail head-engaging part of the bar to convert it primarily into what may be termed a bearing filler in supporting engagement with the rail head, and at the same time utilizing it to transmit the load stresses more directly to that portion of the bar wherein the fibres are scientifically disposed to more adequately meet the requirements of the maximum stresses.

With the above and other objects in view which will more readily appear as the nature of the invention is better understood the same consists in the construction, combination and arrangement of parts hereinafter more fully described, illustrated and claimed. A preferred and practical embodiment of the invention is shown in the accompanying drawings, in which:—

Figure 1 is a perspective view of a joint bar embodying the present improvements.

Figure 2 is a perspective view of the continuous type of joint bar embodying the present improvements.

Figure 3 is a perspective view of the outside of the bar shown in Fig. 2.

Figure 4 is a diagrammatic view illustrating the theory of the present invention.

Similar reference numerals designate corresponding parts throughout the several figures of the drawings.

Primarily, the invention provides a joint bar structure having means for a better balancing of the useful metal so that the bar will more adequately meet the requirements of the maximum stresses. Also, in its application to the top part or head of the bar to provide means for deflecting the load stress to a point below the less useful metal located the farthest from the neutral axis of the bar.

Although the invention is useful in connection with the ordinary type of angle bar, its underlying principle may be applied with equal facility to bars of the continuous type with a view of establishing a more useful ratio between the section modulus of the top of the bar and the section modulus of the bottom of the bar. And, it is to be understood that the present invention includes within its scope the modification of either

the head of the joint bar, or of both the head and base portion of the bar; in the latter case, particularly in a bar of the continuous type, wherein as a rule, there is an unduly high ratio of disproportion between the section modulus of the top of the bar and the section modulus of the bottom of the bar.

By reference to Figure 1 which shows a standard type of angle bar 1, it will be observed that the head portion 2 thereof, having the rail engaging face 3, is provided at intervals with fibre interrupting kerfs, produced by transversely notching or cutting through the remote fibres, as indicated at 4. The said kerfs serve to break up the continuity of the fibres in the rail engaging portion of the head 2, thus making in effect at the extreme top of the bar a plurality of relatively independent fillers forming rail-engaging portions 5.

The said kerfs 4 are preferably carried to a depth that substantially defines an upper limit of the useful area of the fibres of the bar which are uniformly spaced from the neutral axis of the bar, and therefore break up the continuity of the fibres of the metal which are most remote from the neutral axis of the bar. These remote fibres theoretically do not enter into the strength of the bar and merely serve the function of a bearing filler to support the head of the rail, thus simply transmitting load stresses from the rail to that portion of the fibres of the head which are adequate to withstand said stresses. The kerfing of the rail contacting surface of the bar to the extent indicated, resulting in the formation of the relatively separate portions 5, also adds to the flexibility of the mass of inert metal at the top of the head of the bar to facilitate the passing of the rail wave motion through the joint.

By reference to Figure 4, which diagrammatically illustrates the theory of the invention, the purpose and effect of the transverse kerfing or notching of the head of the bar will be more readily apparent. In the portion of the bar designated as X the fibres of the metal, by reason of their varying distances from the neutral axis (NA) of the bar have no direct relation to a scientific distribution of the metal which enters into the calculation of the strength of the bar. However, the portion of the metal designated as Y indicates an area in which the fibres are uniformly distant from the neutral axis of the bar, and therefore sustain equal bending strains. In other words, as all of the fibres in the area Y have equal stresses brought upon them, they are better able to withstand the strain imposed thereon than the fibres in the area X wherein the fibres most remote from the neutral axis receive greater strains than others and are therefore more likely to give away and start the bar head to crack. The boundary be-

tween the areas X and Y, in the example shown, therefore constitutes the depth of the kerf in the head of the bar, and this means of determining the depth of the kerfs may be of course applied to bars of any design or type by suitable calculations.

By reference to Figures 2 and 3 it will be observed that the invention may be readily adapted to bars 10 of the continuous type, wherein the head portion 11 is transversely kerfed or notched as at 12 while the base flange 13 may also be provided at its inner edge with the kerfs or notches 14 and a relatively large intermediate kerf or notch 15, while the outside toe portion of the base may also be provided with a central kerf or notch 16. That is to say, to improve the proportionate ratio between the section modulus of the top of the continuous bar and that of the bottom of said bar, it is proposed to notch the base at various points so as to make a more nearly balanced section. By this arrangement the neutral axis is necessarily raised, thus increasing the individual fibre strain in the elements of the base and materially reducing those in the head, the moment of inertia being also reduced, making the bar less stiff while the modulus remain approximately the same. Also this arrangement locates the neutral axis of the bar much nearer the bolt holes which is an additional advantage.

In the case of the continuous bar, the notching of the base as at 14 and 15 is especially advantageous since the effect thereof is to produce a more flexible fitting of the bar to the rail, particularly in the base, thus taking care of slight differences in the rails without gripping the base too tightly. And, in the case of the relatively wide notches 15 and 16 located in the central portions of the base of the bar it is pointed out that these notches materially reduce the transverse sectional area of the base through the midsection of the bar, thereby reducing the superabundance of the tensile strength of the base, as compared with that of the head, to a point where the improved head construction will be adequate to resist rupture because of the more reasonable balancing of the top and bottom sections of the bar adjacent to the abutting rail ends.

It will of course be understood that the invention is particularly susceptible of embodiment in all rolled rail joints, and in carrying the same into effect the formation of the kerfs or notches in the head and base of the bar may be carried out in any suitable manner.

From the foregoing it is believed to be apparent that the novel feature of cutting through the inadequate areas of either the head or base of a joint bar to create a modified portion or area which will more adequately meet the requirements of maximum

stresses, is particularly advantageous since it eliminates cracking of the bar and renders the same more flexible and therefore better adaptable to the carrying of the wave motion in the rails through the joints.

Without further description it is thought that the many features and advantages of the invention will be readily apparent to those skilled in the art, and it will of course 10 be understood that the invention is susceptible of embodiment in any and all types of joint bars, and that the details of the execution may be varied within the scope of the appended claims, without departing from 15 the apparatus and spirit of the invention.

I claim:—

1. A method of confining the stresses in rail joints which consists in removing from the bar inadequate areas of metal remotely 20 located from the neutral axis to thereby deflect the load stress to broader areas of metal below said inadequate areas.

2. A joint bar including a head portion having its rail engaging face transversely 25 notched, the depth of said notches being defined by the limit of the area of unbroken fibres of the metal uniformly distant above the neutral axis of the bar.

3. A continuous rail joint bar having

metal-eliminating notches in its top edge and 30 in the inner edge of its base-member.

4. A method of confining and balancing stresses in a rail joint bar which consists in interrupting the fibres of the metal of the bar located most remote from the horizontal 35 neutral axis thereof.

5. A method of confining and balancing the stresses in a rail joint bar which consists in forming metal removing notches or kerfs at intervals in the bar located most remote 40 from the horizontal neutral axis thereof.

6. A method of balancing the stresses in a rail joint bar which consists in forming notches in the bar transversely of the direction of the fibres of the metal therein. 45

7. A method of balancing the stresses in a rail joint bar which consists in forming notches at intervals in the areas of metal located most remotely from the horizontal neutral axis of the bar and in which the 50 fibres are at non-uniform distances from the said neutral axis.

In testimony whereof I hereunto affix my signature in the presence of two witnesses.
